Primary Examiner — T. Chase Nelson*Assistant Examiner* — Kathleen M Sims(74) *Attorney, Agent, or Firm* — Sarah J. Rhoades**CLAIM**

The ornamental design for a hinged, convertible greenhouse, as shown and described.

DESCRIPTION

FIG. 1 is a front perspective view of a new, ornamental design for a hinged, convertible greenhouse in a fully closed position;

FIG. 2 is a front perspective view of a new, ornamental design for a hinged, convertible greenhouse in a partially open position;

FIG. 3 is a front perspective view of a new, ornamental design for a hinged, convertible greenhouse in a fully open position; FIG. 4 is a first end elevation view of the hinged, convertible greenhouse as shown in FIG. 1;

FIG. 5 is a second end elevation view of the greenhouse as shown in FIG. 1;

FIG. 6 is a rear elevation view of the hinged, convertible greenhouse as shown in FIG. 1;

FIG. 7 is a front elevation view of the hinged, convertible greenhouse as shown in FIG. 1; and,

FIG. 8 is a top plan view of the new, ornamental design for a hinged, convertible greenhouse in the fully closed position as shown in FIG. 1.

The broken line showing of a garden plot and stipple marks representing soil in FIGS. 2 and 3 are included for the purpose of showing environmental context for the hinged, convertible greenhouse and form no part of the claimed design.
